(57) **CLAIM**

The ornamental design for an exercising apparatus, as shown and described herein.

DESCRIPTION

FIG. 1 is a rear, top, left side perspective view according to a first embodiment of my design for an exercising apparatus. FIG. 2 is a rear view of the exercising apparatus shown in FIG. 1.

FIG. 3 is a front view of the exercising apparatus shown in FIG. 1.

FIG. 4 is a right side view of the exercising apparatus shown in FIG. 1.

FIG. 5 is a left side view of the exercising apparatus shown in FIG. 1.

FIG. 6 is a top view of the exercising apparatus shown in FIG. 1.

FIG. 7 is a bottom view of the exercising apparatus shown in FIG. 1.

FIG. 8 is a rear, top, left side perspective view according to a second embodiment of my design for an exercising apparatus.

FIG. 9 is a rear view of the exercising apparatus shown in FIG. 8.

FIG. 10 is a front view of the exercising apparatus shown in FIG. 8.

FIG. 11 is a right side view of the exercising apparatus shown in FIG. 8.

FIG. 12 is a left side view of the exercising apparatus shown in FIG. 8.

FIG. 13 is a top view of the exercising apparatus shown in FIG. 8; and,

FIG. 14 is a bottom view of the exercising apparatus shown in FIG. 8.

The broken lines shown in the figures are for the purpose of illustrating portions of the exercising apparatus which form no part of the claimed design.

1 Claim, 14 Drawing Sheets
